FIG. 4

FIG. 5

FIG. 6

FIG. 7

FIG. 8

To all whom it may concern:

Be it known that I, Harold J. Young, a citizen of the United States, residing at Downey, California, having invented a new, original, and ornamental Design for an Electric Shaver Receptacle, of which the following is a specification, reference being had to the accompanying drawing, forming a part hereof.

Fig. 1 is a top plan view of the electric shaver receptacle showing my new design.

Fig. 2 is a front elevational view of the device shown in Fig. 1.

Fig. 3 is a bottom plan view of the device shown in Fig. 1.

Fig. 4 is a rear elevational view of the device shown in Fig. 1.

Fig. 5 is a left side elevational view of the device shown in Fig. 1.

Fig. 6 is a right side elevational view of the device shown in Fig. 1.

Fig. 7 is a fragmentary sectional view taken at 7—7 in Fig. 2, and

Fig. 8 is a perspective view of the invention.

I claim:

The ornamental design for an electric shaver receptacle, as shown.
